UNITED STATES PATENT OFFICE.

THEODORE EMTMAN, OF LOS ANGELES, CALIFORNIA.

METAL WINDOW-SASH.

1,031,779.

Specification of Letters Patent.

Patented July 9, 1912.

Application filed March 22, 1911. Serial No. 616,239.

To all whom it may concern:

Be it known that I, THEODORE EMTMAN, a citizen of the United States, residing at Los Angeles, in the county of Los Angeles and State of California, have invented a new and useful Metal Window-Sash, of which the following is a specification.

This invention relates to metal window sashes particularly adapted for use in concrete buildings, and the objects of the invention are to obtain the maximum sized opening for the admission of light.

Further objects are to provide a construction which is simple and economical of manufacture, durable in use and which will be perfectly weather-proof.

Referring to the drawings: Figure 1 is a front elevation of a window having sashes constructed in accordance with my invention. Fig. 2 is a vertical sectional view on line x^2-x^2 Fig. 1. Fig. 3 is a section on line x^3-x^3 Fig. 2. Fig. 4 is a perspective view in detail of the lower sash.

1 designates the upper sash and 2 designates the lower sash. Each sash consists of two vertical members, each comprising metal Z-bars 3 with inner flanges 4 between which is the glass 5. 6 designates horizontal members also of Z-bars for the upper part of the upper sash and the lower member of the upper sash is formed by an outer Z-bar 7 and an inner angle bar 8. The vertical and horizontal members of each sash are mitered at the corners and are secured together by a single metal strap 9 which is passed completely around the four sides of the sash and the inner flanges of the respective sash bars are secured by bolts 10 to the strap 9.

The lower sash member of the lower sash is constructed similarly to the lower member of the upper sash, but the upper member of the lower sash has a flat bar 11 which extends outwardly as a flange and is adapted to overlap and fit against the adjacent projecting portion of the angle bar 8 of the upper sash, as clearly shown in Fig. 2, and thereby form a closure between the two sashes when they are in closed position, as shown in Fig. 2.

50 The side flanges of the vertical Z-bars 3 slide between a center bar 12 and angle bars 13 secured to a plate 14 which closes a recess 15 formed in the concrete wall 16, the plate

14 being secured by bolts 17. The manner of forming the pocket 15 is disclosed in a 55 companion application of mine filed March 22, 1911, Serial No. 616,240. 18 designates the weights. As shown in Fig. 2, a rubber cleat 19 is arranged on the stool 20 and serves to make a weather-tight closure at 60 this point in addition to preventing noise or jarring the sash when it is lowered.

In the form shown in Figs. 5 and 6, the glass 21 is secured between vertical Z-bars 22, in both upper and lower sash. In the 65 upper sash horizontal Z-bars 23 are arranged at the top of the sash to retain the glass and at the bottom of the upper sash angle bars 24 are employed. At the upper part of the lower sash angle bars 25 are employed and at the lower part one Z-bar 26 and one angle bar 27 are employed. In both 70 upper and lower sash the vertical and horizontal bars are mitered and secured together by a single metal strap 28 which 75 passes around the bars. Secured to the upper part of the lower sash outside of the strap 28 is a horizontal flat bar 29 which is adapted to lap over a similar bar 30 on the lower part of the upper sash and form a 80 closure between the two sashes.

Each sash is pivotally mounted to a pair of slides, each slide comprising a channel bar 31 which slides between a vertical angle bar 32 and a bar 33 secured to a plate 34 85 which closes an opening 35 in which are the weights 36.

The trunnions 37 secured to the strap 28 have studs 38 which are journaled in the slides 31 and permit the sashes to be turned. 90

What I claim is:

A window comprising a sash formed of vertical Z-bars, horizontal Z-bars at one end of the sash, a horizontal Z-bar at the other end of the sash, an angle bar at the latter end, and a metal strap extending around the four sides of the sash and securing said bars between the outer flanges thereof. 95

In testimony whereof, I have hereunto set my hand at Los Angeles, California, this 100 23rd day of February, 1911.

THEODORE EMTMAN.

In presence of—

G. T. HACKLEY,
FRANK L. A. GRAHAM.
